APPARATUS FOR THE DIGESTION OF NITROCELLULOSE

Application filed May 29, 1929. Serial No. 366,921.

My invention relates to an improvement in method and apparatus for the treatment of nitrocellulose, and more particularly relates to a method and apparatus for the digestion 5 of nitrocellulose to effect reduction of its viscosity, increase its stability, and for its purification.

As is well known in the production of nitrocellulose, cellulose, as for example cotton, is subjected to nitration, then washed to free it from acids, then subjected to a boiling treatment or digestion and finally subjected to further washing or other treatment for its purification. In the production of 10 nitrocellulose heretofore the boiling treatment or digestion of the nitrated cellulose has been carried out in large closed digesters, containing, for example, 1000 cubic feet of water and 4000 pounds of nitrocellulose, the 15 mass being heated to a temperature of from 115° C.-132° C. for a period ranging from ten hours to thirty hours depending upon the nitrogen content of the nitrocellulose, by the circulation through the nitrocellulose of heated water. Such procedure for the digestion 20 of nitrocellulose is disadvantageous for many reasons, chief among which are that it is impossible to quickly and uniformly heat the large mass of nitrocellulose, the 25 large mass is a source of danger, the nitrocellulose tends to pack and the removal of entrapped air and gas, which tends to keep portions of the mass out of contact with the water, is difficult.

Further it has been found in the case of 30 nitrocotton, that due to packing, when the nitrocotton loses its strength during the digestion, it is impractical to produce a nitrocotton with a viscosity much below one-half.

Now it is the object of my invention to provide a novel method and apparatus for the digestion of nitrocellulose whereby the disadvantages of the prior procedure will 35 be eliminated and whereby a nitrocellulose of reduced viscosity and of greater stability and purity than heretofore will be produced.

In accordance with my invention nitrocellulose, after removal from the nitrating 40 bath and washing for the removal of acids,

is forced under pressure together with a carrier liquid, as water, through a restricted passage, as a coil of relatively small cross section, and provided with means adapted to control the discharge from the passage and effect a substantial equalization of the pressure in the coil between the inlet and discharge ends, such as a standpipe, connected to the discharge end of the passage and adapted to afford a head or back pressure, 55 or a restricted outlet provided by reducing the discharge end of the passage or providing a valve thereon. The mixture of carrier liquid and nitrocellulose pass through the passage together at a relatively high velocity 60 and at a regulated temperature. On passing out of the passage the nitrocellulose 65 may be subjected to such further treatment as is desired.

Further, my invention contemplates the 70 provision of means for supplying additional carrier liquid to the mixture of nitrocellulose and carrier liquid at a point adjacent the outlet from the coil, thus facilitating discharge of the nitrocellulose-carrier liquid 75 mixture and avoidance of jamming and at the same time assisting in washing out acid from the nitrocellulose and hence promoting its stability.

Having now indicated in a general way 80 the nature and purpose of my invention, I will proceed to a more detailed description thereof with reference to the accompanying drawing in which an apparatus in accordance with my invention is shown diagrammatically, a form of valve for controlling 85 the outlet from the coil being shown in section.

In the apparatus illustrated A indicates 90 an agitating tub for the reception of nitrated cellulose to be digested and in which the nitrated cellulose is mixed with a carrier liquid, as water. B indicates a pump adapted for drawing nitrated cellulose and water from the tub A and forcing the mixture into and through the passage or coil C which is formed, for example, from a number of pipe sections connected by return bends. D indicates a tank for collecting the 95 treated nitrocellulose. A portion of the coil 100

at the inlet end is jacketed as indicated at *e*, the jacket being provided with an inlet and outlet for steam adapted for heating the nitrocellulose and water, and a portion 5 of the coil at its outlet end is jacketed as indicated at *f*, the jacket *f* being provided with an inlet and outlet for water adapted for cooling the nitrated cellulose and water. The intermediate portion of the coil is preferably 10 covered with insulating material, for example asbestos, as indicated at *g* in order to maintain the desired temperature of the nitrocellulose and water in the intermediate portion of the coil.

15 *H* indicates a valve comprising a casing adapted for connection to the outlet end of the coil *C* and to a pipe *i* connected to a standpipe *X*. Within the casing is provided a valve seat on which is adapted to 20 seat a conical valve *j*, the valve being desirably arranged in line with the outlet from the coil. The stem *k* of valve *j* extends externally of the casing through a stuffing box *l* and is provided at its outer end with a 25 head *m* against which one end of a spring *n* abuts. The other end of spring *n* abuts against a stop *o* adjustably carried by a bracket *p* attached to the casing. The valve *j* is thus 30 yieldingly held on its seat by spring *n*, the tension of which is set to permit the valve to normally open against a given pressure in the coil *C* and at the same time permit further opening of the valve to free any jam of nitrocellulose 35 which may occur at the valve due to the packing tendency of the nitrated cellulose.

Adjacent the outlet end of the coil *C* just ahead of the valve *H* a pipe *E* is let into the coil and connected to the discharge of a 40 pump *F*, to the intake of which is connected a pipe *G* leading from a suitable supply of water, either an independent supply or that in or overflowed from tank *D*. The passage of water through pipe *E* is controlled by a 45 valve *I*.

The standpipe *X*, which forms a chamber, extends vertically a sufficient distance to provide a desirable head or back pressure and is provided with a return bend and 50 downward extension *X'* connected with the tank *D*. A vent pipe *Y*, controlled by a valve *Z*, is connected to the downward extension *X'* of the standpipe in order to avoid or control the creation of a vacuum, 55 and a pipe *R*, controlled by a valve *S*, is connected to the standpipe and to a suitable source of air under pressure whereby the pressure created by the head in standpipe *X* may be relieved. Further, a direct connection 60 between the end of coil *C* and tank *D* is made through a pipe *T* controlled by a valve *u*, whereby direct discharge from the coil *C* to tank *D* may be effected in cases of emergency.

65 While I have described the apparatus in

accordance with my invention, as diagrammatically illustrated, as including both a discharge control valve *H* and a standpipe *X*, it will be understood that the apparatus will be effective with the use of a standpipe 70 only for control of the discharge from the coil through the back pressure from the head therein.

As a more specific example of a form of apparatus for use in connection with the 75 digestion of, for example nitrocotton, the various elements are preferably made of chrome steel, the coil may desirably have a diameter of three and one-half inches, and a length of say 2500-3000 feet while the 80 standpipe *X* may be of a diameter of three and one-half inches and of a height of 168 feet, affording a pressure of 72 pounds or such as to afford a desirable head, depending upon the pressure desired in the 85 coil.

In the treatment of nitrocotton with the apparatus above described, and according to the method embodying my invention, and which forms the subject matter of the co-pending application filed by me February 23, 1928, Serial No. 256,140, for example, nitrocotton, is placed in the tub *A* with water in about the proportion of one nitrocotton to twenty-five water, the tub being 90 desirably provided with an agitating device for mixing the nitrocotton and water. The mixture of nitrocotton and water is pumped through the coil at a pressure of about 80 pounds per square inch, and at a substantial 95 velocity, say, for example, about two feet per second, and the mixture of nitrocotton and water in the coil is brought to a suitable temperature, (say about 160° C.) by the introduction of steam into the jacket 100 *e*. A preferred range of temperature is from about 130° C. or possibly somewhat lower to about 160° C., although a temperature as high as 180° C. may be permissible. The valve *j* is set so as to permit the nitrocotton and water to discharge into the standpipe *X* to be finally discharged into tank *D* and, as has been indicated, jamming of the nitrocotton is prevented by the fact that the valve is yieldingly held and on a building up of pressure, due to jamming of nitrocotton, will open wider and permit the passage of any jammed or matted nitrocotton. During the treatment water under pressure is forced into the coil *C* adjacent to valve 110 *H*, through pipe *E*, and acts to insure operation of the valve *H* on jamming of the nitrated cotton and also to maintain the valve normally at a desired open position. The water introduced into coil *C* through pipe *E* 115 also acts to increase the proportion of water to nitrated cotton at the point of discharge from the coil, thus facilitating the discharge of the mixture and acting to wash out acidity from the nitrated cotton. The water ad-

120 125 130 135 140 145 150 155 160 165 170 175 180 185 190 195 200

mitted through pipe E may, as has been indicated, be drawn from an independent supply, or it may be drawn from tank D directly or indirectly, thus in effect recirculating a part of the water from the nitrated cotton-water mixture discharged from the coil. The water may be heated or at room temperature, and may be introduced into the coil in quantity and under pressure varying with the characteristics of the mixture and pressure within the coil and with the desired control of valve H.

After passing through valve H the nitrocotton and water will pass into standpipe X in which it will rise to pass eventually to tank D through the downward extension X'. The column of nitrocotton and water in the standpipe X will afford a head or back pressure on the valve H, which will be effective to control the action of the valve and the discharge from the coil.

In the operation of the apparatus described the discharge from coil C will, as has been indicated, be controlled by the valve H and the head afforded in the standpipe X, with the result that a substantial equalization of pressures in the coil C will be effected. Where both the standpipe X and the valve H are used the head afforded in the standpipe will act to balance valve H, to insure smooth and controlled action of the valve in its operation in relieving any jam which may occur, and with valve H to control the discharge from coil C. However, the apparatus, as will be clearly understood, may be constructed without the valve H, control of the discharge being obtained by use of the standpipe only, which in such case is connected directly to the discharge end of the coil C. When the valve H is omitted, it is only necessary to provide the standpipe X of sufficient height, or alternatively, a suitable chamber, to provide a head affording sufficient pressure for such control of the discharge from coil C as is necessary to obtain a substantial equalization of pressure in the coil. Further, it will be clearly understood that the apparatus may be constructed without the standpipe X, control of the discharge from coil C being affected by the valve only, as fully described and claimed in the copending application filed by me July 14, 1928, Serial Number 292,808.

In connection with the apparatus embodying my invention, it will be noted that means, including the pipe R, are provided for releasing the back pressure from the head in standpipe X when desirable and, including the pipe T, for discharging directly from the coil C into tank D when desired or in cases of emergency.

In connection with the apparatus herein described and embodying my invention, it will be understood that various modifica-

tions and changes may be made therein without departing from my invention.

It will be understood that the apparatus embodying my invention may be used for the treatment of cellulose other than nitrocellulose, as for example, in connection with the purification treatment of cellulose, such as cotton, straw, comminuted wood, or the like.

This application constitutes a continuation in part of application for patent for improvement in apparatus for the digestion of nitrocellulose, filed by me July 14, 1928, Serial No. 292,808.

What I claim and desire to protect by Letters Patent is:

1. Apparatus for the treatment of fluent material comprising a solid suspended in a carrier liquid, including in combination an extended conduit, means for forcing fluent material through said conduit, means for cooling fluent materials adjacent the discharge end of said conduit and means for creating a hydrostatic head exerting pressure on fluent material within said conduit in opposition to said forcing means.

2. Apparatus for the treatment of fluent material comprising a solid suspended in a carrier liquid, including in combination an extended conduit, means for forcing fluent material through said conduit, means for heating fluent material within said conduit, means for cooling fluent material adjacent the discharge end of said conduit, and means for creating a hydrostatic head exerting pressure on fluent material within said conduit in opposition to said forcing means.

3. Apparatus for the treatment of fluent material comprising a solid suspended in a carrier liquid, including in combination an extended conduit, means for forcing fluent material through said conduit, means adjacent the inlet end of said conduit, for heating fluent material within said conduit, means adjacent the discharge end of said conduit for cooling fluent material within said conduit, means for maintaining the temperature of fluent material within said conduit between the heating and cooling means, and means for creating a hydrostatic head exerting pressure on fluent material within said conduit in opposition to said forcing means.

4. Apparatus for the treatment of fluent material comprising nitrocellulose and a carrier liquid, including in combination a conduit of substantial length and of relatively small cross-sectional area, means for forcing fluent material through said conduit, means for heating fluent material within said conduit adjacent the inlet end thereof, means for cooling fluent material within said conduit adjacent the discharge end thereof, and a standpipe connected to the discharge end of said conduit and adapted to receive fluent

material discharged from said conduit and to contain a column thereof exerting hydrostatic pressure in opposition to said forcing means.

- 5 5. Apparatus for the treatment of fluent material comprising nitrocellulose and a carrier liquid, including in combination a conduit having sections extending horizontally and sections extending upwardly, means for 10 forcing fluent material through the conduit from its inlet end and means for exerting a hydrostatic head on fluent material within the conduit in opposition to said forcing means.
- 15 6. Apparatus for the treatment of fluent material comprising nitrocellulose and a carrier liquid, including in combination, a conduit having sections extending horizontally and sections extending upwardly, means for 20 forcing fluent material through the conduit from its inlet end, a standpipe adapted to receive fluent material discharged from said conduit and to contain a column thereof exerting hydrostatic pressure in opposition to 25 said forcing means.
7. Apparatus for the treatment of fluent material comprising nitrocellulose and a carrier liquid including in combination, a conduit of substantial length and of relatively 30 small cross sectional area comprising a plurality of horizontally extending sections connected together by return bends, the inlet end of the said conduit being located at a level below its discharge end, means for forcing 35 fluent material through the conduit from its inlet end and a standpipe adapted to receive fluent material discharged from said conduit and to contain a column thereof exerting hydrostatic pressure in opposition to 40 said forcing means.

In testimony of which invention, I have hereunto set my hand, at Parlin, New Jersey, on this 24th day of May, 1929.

CERTIFICATE OF CORRECTION.

Patent No. 1,911,201.

May 30, 1933.

MAHLON G. MILLIKEN.

It is hereby certified that error appears in the printed specification of the above numbered patent requiring correction as follows: Page 1, line 40, after "one-half" insert the word "second"; and that the said Letters Patent should be read with this correction therein that the same may conform to the record of the case in the Patent Office.

Signed and sealed this 22nd day of August, A. D. 1933.

(Seal)

**M. J. Moore.
Acting Commissioner of Patents.**
